22 Claims. (Cl. 68—131)

1

Our invention relates to apparatus for washing clothes with the aid of an oscillatable agitator.

In washing clothes in a body of washing fluid in a receptacle or vat of a washing machine by mechanical action, it is desirable for all of the clothes to be subjected to the same thorough cleansing and washing action. When such washing action is effected by an agitator or stirrer oscillatable in the receptacle or vat, the washing action is accomplished by intermittent compression and loosening of the clothes which are alternately acted upon at opposite faces or sides of the agitator element.

It is an object of our invention to provide an improved apparatus for washing clothes with the aid of an oscillatable agitator, particularly to effect a more efficient and uniform washing of the clothes.

It is a further object to provide an improved agitator which imparts movement to the washing fluid and the clothes being circulated in a receptacle which is extremely favorable for effecting a thorough cleaning and washing action.

It is a further object to produce such movement of the washing fluid and the clothes in the receptacle with the aid of an oscillatable agitator which is formed and shaped so that the clothes being circulated are repeatedly brought back again and again to be acted upon by the agitator, and hence frequently exposed to its favorable cleansing and washing action.

In accordance with our invention, efficient cleansing and washing of the clothes may be accomplished, if desired, by a single oscillatable agitator of such form that the clothes are circulated in a path of movement in which the latter are more or less uniformly acted upon by the agitator. On alternate strokes of its oscillatory movement, one part of the agitator is effective to impart movement to the clothes in one general direction past the agitator; and on opposite alternate strokes of its oscillating movement, another part of the agitator is effective to impart movement to the clothes in a generally opposite direction past the agitator. This movement imparted not only to the clothes but also to the washing fluid promotes a positive circulation of the clothes in a path of movement in which the clothes can be repeatedly brought into physical contact with different parts of the agitator, each part contributing to the cleaning and washing action and imparting such a movement to the clothes that the clothes pass to another part of the agitator.

2

In its preferred form the oscillatable agitator is provided with two blades or impellers, each of which extends lengthwise of the axis of oscillation and is bent or curved in transverse section so as to define a generally concave-shaped blade surface at one face thereof and a convex-shaped blade surface at the opposite face thereof. The blades in transverse section are bent or curved in opposite directions with respect to the axis of oscillation, the outer free edge portion of each blade or impeller projecting in the general direction the clothes move from one side or face to the opposite side or face of the blade past its outer free edge.

15 The effective parts of the blades or impellers desirably are offset with respect to one another lengthwise of the agitator, and are at an angle with respect to the axis of oscillation which is less than 180°, so that the concave-shaped blade surfaces, which may be referred to as being bowl-shaped, face and oppose each other. The two blades extend lengthwise of the agitator along all or a part of its length and the convex-shaped blade surfaces or outer faces remote from each other are smooth and merge into one another to present a surface which is free of obstruction at all regions thereof and over which the clothes readily slide during oscillating movement of the agitator.

20 The blades during oscillating movement of the agitator pass through regions of the body of washing fluid that are otherwise free and unobstructed for a sufficient distance beyond the outer free edges of the blades to enable clothes to move in one direction past each outer blade edge from the convex-shaped face to the concave-shaped face of the blade.

The agitator may be mounted in a washing receptacle for oscillating movement about a horizontally extending axis in such a manner that the blades project toward the bottom of the receptacle during their oscillating movement. To facilitate loading of the clothes into the receptacle and cleaning of the latter, the agitator is desirably removably supported in the receptacle to permit its ready removal from the washing apparatus.

25 The invention, together with the above and other objects and advantages thereof, will be more fully understood from the following description taken in conjunction with the accompanying drawings forming a part of the specification, and of which:

30 Fig. 1 is a vertical view, partly in section, of

apparatus for washing clothes embodying the invention;

Fig. 2 is an enlarged side elevation of the agitator shown in Fig. 1;

Fig. 3 is an end view of the agitator, taken on line III—III of Fig. 2;

Fig. 4 is a top plan view of the agitator shown in Figs. 1 to 3;

Fig. 5 is a vertical sectional view taken on line V—V of Fig. 2;

Fig. 6 is a horizontal sectional view taken on line VI—VI of Fig. 2;

Figs. 7 and 9 are top plan views, more or less diagrammatically illustrating washing apparatus like that shown in Fig. 1, to show more clearly the manner in which washing fluid and clothes are circulated in a receptacle, the agitator being at opposite limits of its oscillating movement in Figs. 7 and 9, respectively;

Fig. 8 is a vertical view, more or less diagrammatically illustrating washing apparatus like that shown in Fig. 1, to show more clearly the manner in which clothes are acted upon by the blades of the agitator during its oscillating movement;

Fig. 10 is an enlarged fragmentary sectional view of parts of the clothes washing apparatus of Fig. 1 to illustrate details of supporting structure for removably holding the agitator; and

Fig. 11 is a vertical sectional view similar to Fig. 5 illustrating another form of the agitator.

Referring to Fig. 1, the clothes washing apparatus embodying the invention comprises a vat or receptacle 10 for holding a body of washing fluid. The receptacle 10 is formed with a flat bottom 13 and an upstanding side wall at the upper peripheral edge of which may be provided an outwardly extending flanged rim 12. The flanged rim 12 may be utilized for positioning the receptacle in an opening in a suitable supporting surface, such as, for example, a scullery sink. The flanged rim 12 also provides a shoulder upon which a cover 11 is supported to prevent spilling of washing fluid. Although not shown, the cover 11 may be provided with a suitable handle to facilitate handling thereof.

A driving unit 14, which may be of any conventional type including an electric motor and suitable gearing, is diagrammatically shown at the side wall of the receptacle 10. The driving unit 14 is operatively connected in any well known manner to an agitator 15 for oscillating the latter.

In accordance with the invention, the agitator 15 is mounted in the receptacle 10 for oscillating movement therein about a horizontally disposed shaft 16. The agitator 15 is removably supported in the receptacle 10 to permit positioning and removal thereof at any time, thereby avoiding any interference with the loading and removal of clothes into and from the receptacle 10 during a washing operation and facilitating the cleaning of the receptacle. This may be accomplished by providing an enlarged part 21 at one end of the agitator 15 which serves as a clutch element adapted to engage another clutch element driven by the driving unit 14. The shaft 16 about which the agitator 15 oscillates includes a stub shaft or pin 22 which projects from the opposite end of the agitator and is formed with an enlarged outer end 20.

As best shown in Fig. 10, the agitator 15 is formed with a hollow sleeve 32 which receives the inner end of the stub shaft 22 having an elongated slot 33. A pin 34 fixed to the sleeve 32 limits axial movement and prevents angular movement of the stub shaft 22. A hollow bushing

35 fixed to the side wall of the receptacle 10 receives the enlarged end 20 of the stub shaft 22 which is urged to the right in Fig. 1 under the compression of a spring 36 disposed between the inner end of the stub shaft 22 and a pin 37 fixed to the hollow sleeve 32.

When it is desired to remove the agitator 15 from the receptacle 10, it is moved to the right in Fig. 1 against the action of spring 36 until the clutch element 21 is disengaged from its cooperating clutch element associated with the driving unit 14. The left-hand end of the agitator 15 can then be tilted upwardly, as indicated in dotted lines in Fig. 1, after which the agitator can be readily removed from the receptacle. To facilitate the positioning and removal of the agitator 15, the enlarged end 20 of the stub shaft 22 may be suitably rounded or curved and the hollow bushing 35 may be formed with a spherical cavity, if desired.

The agitator 15 comprises a pair of elongated blades or impellers 18 and 19 each of which extends lengthwise of the axis of oscillation across a major portion of the distance between the opposing sides of the receptacle 10. As best shown in Figs. 7 and 9, the receptacle 10 may be of cylindrical shape with the axis of oscillation of the blades 18 intersecting the vertical axis of the receptacle. When the agitator 15 is in an intermediate position of its oscillating movement and approximately midway between the limits of its back and forth motion, the blades 18 and 19 are directed obliquely downwardly toward the bottom 13 of the receptacle, as best shown in Fig. 3.

Each blade 18 and 19 in transverse section is curved so as to define a concave-shaped blade surface at one face and a convex-shaped blade surface at its opposite face. As seen in Fig. 3, the blades 18 and 19 are curved in opposite directions with respect to the axis of oscillation so that the concave-shaped blade surfaces 23 and 24 face and oppose each other.

The remote convex-shaped blade surfaces 25 and 26 desirably form an angle with respect to the axis of oscillation which is less than 180°. It will be seen that the convex-shaped blade surfaces 25 and 26 are imperforate, smooth and free of obstructions of a character to which clothes tend to cling or stick. Further, the imperforate convex-shaped blade surfaces embrace the shaft 16 and hence extend directly to the axis of oscillation, thus merging into one another to present an over-all surface which is characterized by an unbroken soft curve extending from the region 55 of the shaft 16 to the outer free edges of the blades and over which clothes readily slide during oscillating movement of the agitator 15.

The outer free edge of each blade 18 and 19 is formed with an enlarged bead 31 which is rounded and extends inwardly toward the concave-shaped blade surface. The beads 31 are effectively employed to impart movement to the clothes, as will be described presently, and are shaped to keep the outer or remote sides 25 and 26 of the blades 65 smooth and free of obstruction of any kind.

The inner faces 23 and 24 may be formed to present irregular shaped surfaces to promote movement of the clothes by each concave-shaped blade surface when it is the leading face during 70 oscillating movement of the agitator 15. This may be accomplished by forming grooves or providing rounded projections at the opposing inner faces 23 and 24 of the blades, if desired. In the embodiment shown in Fig. 11, the inner face 24 75 of the blade 19 is formed with grooves or serra-

tions which extend lengthwise of the agitator 15 and are more or less parallel to the axis of oscillation.

In the preferred embodiment illustrated, the blades are more or less of parabolic form and are not only curved in transverse section, but also curved in longitudinal section, as best seen in Fig. 6, to provide bowl-shaped blades which face the vertical plane F—F midway between the blades and passing through the axis of oscillation at the region of shaft 16.

The extent to which the blades 18 and 19 project laterally from the axis of oscillation varies lengthwise of the agitator 15. The regions of the blades 18 and 19 of widest lateral extent are desirably offset or displaced with respect to one another lengthwise of the agitator 15. As shown in Fig. 2, the region A of widest lateral extent of the blade 18 is adjacent to one end 29 of the agitator, and the region B of widest lateral extent of the blade 19 is adjacent to the opposite end 30 of the agitator.

The lateral extent of the blade 18 becomes progressively smaller in a direction extending lengthwise of the agitator from the widest region A to the opposite end 30 of the agitator. Likewise, the lateral extent of the blade 19 becomes progressively smaller in a direction extending lengthwise of the agitator from the widest region B to the opposite end 29 of the agitator. At a centrally disposed region C intermediate the ends of the agitator, at which point the outer free edges of the blades 18 and 19 intersect, the lateral extent of each blade is less than one-half of its widest lateral extent.

Also, the perpendicular distance from the inner face of each bowl-shaped blade 18 and 19 to a plane which is midway between the blades and passes through the axis of oscillation varies lengthwise of the agitator. This is best shown in Fig. 6 where the perpendicular distance to the plane F—F from the inner faces 23 and 24 of the blades is greatest at the regions G adjacent to and slightly removed from the extreme ends 29 and 30 of the agitator, and less at the regions H directly at the ends 29 and 30 of the agitator than at the regions J intermediate and between the ends of the agitator.

During a washing operation in which the receptacle contains a body of washing fluid and the clothes to be washed, a general movement of the clothes takes place from the convex-shaped side to the concave-shaped side of each blade past its outer extremity or free edge. The oscillating movement of each blade 18 and 19 lifts and presses down the clothes, thereby alternately compressing and loosening the clothes and effecting a washing action.

When the blade 19 moves to the left in Fig. 5 and through a suitable angle from the position illustrated, the clothes upon which the concave-shaped blade surface 24 acts are also moved to the left. When the blade 19 moves in the opposite direction and to the right in Fig. 5, there is a tendency for the clothes in the path of movement to be moved backward somewhat. However, as the blade 19 continues to move toward the right in Fig. 5, the clothes readily slide off the convex-shaped blade surface 26 at the outer free edge of the blade due to its contour and the fact that it is smooth and free of obstruction of any kind.

When the convex-shaped blade surface of each blade is the leading face, it acts more or less passively on the clothes in its path of movement

while the concave-shaped blade surface of each blade positively acts upon and seizes the clothes, such action being effective to entrain the clothes and impart a generally forward movement thereto which is initially in a downward direction and subsequently in an upward direction. By providing the beads 31 at the outer free edges of the blades, the seizing of the clothes is improved when the concave-shaped blade surface of each blade is the leading face during oscillating movement of the agitator 15. The seizing action of the clothes is further improved by providing grooves, such as the serrations shown in Fig. 11, for example, at the concave-shaped faces of the blades.

In the embodiment illustrated and just described, the agitator 15 is placed in a washing position with its axis of oscillation alongside of and adjacent to the surface level 17, as indicated in Fig. 8. The surface level 17 is a bounding surface of the body of washing fluid of such size that the blades 18 and 19 oscillate back and forth through an arc in which the blades pass through a region of the body of fluid which is otherwise unobstructed. The unobstructed region extends downwardly from the surface level 17 for a sufficient distance to provide adequate space to enable clothes to slide off the convex-shaped blade surfaces into such space and permit the blades to complete their backward strokes past the clothes. The distance between the flat bottom 13 and the extremities or outer free edges of the blades 18 and 19 varies during oscillating movement of the agitator 15 and increases as the blades move from an intermediate vertical position to an inclined position with each stroke of oscillation.

With oscillatory movement of the agitator 15 and the repeated back and forth strokes of the blades 18 and 19, a general movement of the clothes is promoted from the convex side to the opposite concave side of each blade past its outer extremity. Since the blades 18 and 19 are staggered with respect to one another lengthwise of the agitator 15, and the bowl-shaped surfaces 23 and 24 face each other, the blades effectively work alongside of each other and the clothes to be washed are caused to move past the agitator in opposite directions in two streams beside each other, as indicated by the arrows D and E in Fig. 6.

In the receptacle 10 these streams, indicated by the arrows D and E, mutually cooperate to produce circulation of the clothes in one single direction. This is best illustrated by referring to Fig. 7 which diagrammatically shows the concave-shaped face of the blade 18 acting upon the clothes and imparting movement thereto toward the left at one side of the receptacle 10. Fig. 8 diagrammatically illustrates the blade 18 in a position corresponding to that shown in Fig. 7, in which the blade 18 is moving toward the left and acting upon the clothes at its concave-shaped side or face.

In Fig. 9 the blade 19 is shown at the completion of a forward stroke in which the concave-shaped face thereof has acted upon the clothes. During such forward stroke of the blade 19, movement is imparted to the clothes to the right and in the opposite direction from that shown in Fig. 7. In the receptacle 10 these oppositely directed movements imparted to the clothes by the blades 18 and 19 augment each other to circulate the clothes in one general direction, the upstanding side wall of the receptacle contributing to move the clothes in a circular path of movement which is generally parallel to the surface level 17 of the

body of washing fluid. This movement of the clothes in one general direction is also supplemented by an additional vertical movement at the regions of the blades 18 and 19 which causes the clothes to move down and up while being carried forward by the bowl-shaped surfaces 23 and 24 of the blades.

It will now be understood that the clothes are circulated in such a manner that they are repeatedly brought back again and again to be acted upon by the agitator and circulation of the clothes in a path of movement avoiding the blades 18 and 19 is minimized and substantially prevented. The movement thus imparted to the clothes contributes to an efficient and uniform washing action without subjecting the clothes to excessive wear and deterioration.

The agitator 15 is formed of an integral body of material having the blade-forming portions 18 and 19 which are unsymmetrically disposed with respect to the axis of oscillation at the region of the shaft 16. The agitator 15 is formed with an elongated sleeve 32 which may be referred to as the axis-forming region where the imperforate blade-forming portions 18 and 19 merge into one another.

In view of the foregoing, it will now be understood that an improvement has been provided for washing clothes with an oscillatable agitator in which efficient and uniform washing of the clothes is accomplished. In the foregoing description and in the claims it is to be understood that the term "clothes" is intended to include not only wearing apparel but other textile fabrics or materials which require washing.

Although a single embodiment of the invention has been shown and described, it will be apparent to those skilled in the art that various modifications and changes may be made without departing from the spirit and scope of the invention. For example, in certain instances it may be desirable to mount the agitator in the receptacle for oscillation about an axis which is slightly inclined to the horizontal. It is, therefore, contemplated to cover all modifications and changes which come within the spirit of the invention, as pointed out in the following claims.

We claim:

1. In a washing machine, a receptacle, an agitator, means for mounting said agitator in said receptacle for oscillating movement about a horizontally extending axis, said agitator including a pair of blades extending laterally from such axis, each of said blades being curved so as to be concave on one side and convex on the other side and the curvature of one blade with respect to the axis being in a direction opposite to that of the curvature of the other blade with respect to the axis, each of said blades having a lateral extent varying along the axis of the agitator, the maximum lateral extent of one blade being displaced axially with respect to the maximum lateral extent of the other blade.

2. In a washing machine, a receptacle, an agitator, means for mounting said agitator in said receptacle for oscillating movement about a horizontally extending axis, said agitator including a pair of blades extending laterally from each axis, each of said blades being curved so as to be concave on one side and convex on the other side and the curvature of one blade with respect to the axis being in a direction opposite to that of the curvature of the other blade with respect to the axis, each of said blades having a lateral extent varying along the axis of the agitator, the maxi-

mum lateral extent of one blade being located adjacent to one end of said agitator and the maximum lateral extent of the other blade being located adjacent to the opposite end of the agitator.

3. In a washing machine, a receptacle, an agitator, means for mounting said agitator in said receptacle for oscillating movement about a horizontally extending axis, said agitator including a pair of blades extending laterally from such axis, each of said blades being curved so as to be concave on one side and convex on the other side and the curvature of one blade with respect to the axis being in a direction opposite to that of the curvature of the other blade with respect to the axis, each of said blades having a lateral extent varying along the axis of the agitator, the maximum lateral extent of one blade being located adjacent to one end of said agitator and the maximum lateral extent of the other blade being located adjacent to the opposite end of the agitator, the lateral extent of each of said blades at the point midway between the ends of said agitator being less than one-half of its maximum lateral extent.

4. In a washing machine, a receptacle, an agitator, means for mounting said agitator in said receptacle for oscillating movement about a horizontally extending axis, said agitator including a pair of blades extending laterally from such axis and disposed at an angle of less than 180° with respect to each other, each of said blades having a varying lateral extent, the maximum lateral extent of one blade being located adjacent to one end of said agitator and the maximum lateral extent of the other blade being located adjacent to the opposite end of the agitator, the distance between each blade and an axial plane located symmetrically with respect to said blades decreasing from the point of maximum lateral extent towards the opposite end of the blade, the adjacent faces of said blades being concave and the remote faces being convex.

5. In a washing machine, a receptacle, an agitator, means for mounting said agitator in said receptacle for oscillating movement about a horizontally extending axis, said agitator including a pair of blades extending laterally from such axis, each of said blades being curved so as to be concave on one side and convex on the other side and the curvature of one blade with respect to the axis being in a direction opposite to that of the curvature of the other blade with respect to the axis, each of said blades having a lateral extent varying along the axis of said agitator, one of said blades having an axially extending portion of maximum lateral extent disposed between one end of said agitator and a region intermediate the ends thereof and said other blade having an axially extending portion of maximum lateral extent disposed between the opposite end of said agitator and a region intermediate the ends thereof, the convex sides of said blades being substantially smooth and free of obstructions to present surfaces over which clothes to be washed readily slide and the concave sides thereof being formed to present irregular-shaped surfaces which will promote movement of the clothes by each concave side when it is the leading face during oscillating movement of the agitator.

6. In a washing machine, a receptacle for containing washing fluid and clothes, an oscillatable agitator provided with two blades and having its axis of oscillation disposed substantially parallel to the bottom of said receptacle, said agitator at different axially spaced apart regions thereof being asymmetric in sections perpendicular to

the axis of oscillation and disposed with said blades extending obliquely down towards said bottom when the agitator is midway between its extreme positions of oscillation, said agitator being mounted for oscillation in said receptacle so that an unobstructed space is provided between the outer free edges of said blades and the bottom of said receptacle to enable clothes in the path of movement of said blades, when the remote faces thereof are the leading faces during oscillating movement of said agitator, to slide off such remote faces into said space at the outer free edges of said blades and allow the latter to complete their oscillating movement past the clothes, said receptacle being of such shape that the distance between the bottom of the receptacle and the outer free edges of said blades varies during oscillating movement of said agitator.

7. In a washing machine, a receptacle for containing washing fluid and clothes, an agitator, and means for mounting said agitator for oscillating movement in said receptacle, said agitator including a pair of blades, the adjacent faces of said blades being concave and the remote faces of said blades being convex, each of said blades having a lateral extent varying along the axis of said agitator, one of said blades having an axially extending portion of maximum lateral extent disposed between one end of said agitator and a region intermediate the ends thereof and said other blade having an axially extending portion of maximum lateral extent disposed between the opposite end of said agitator and a region intermediate the ends thereof, the convex surfaces being imperforate and smooth and merging into one another to present a surface which is substantially free of obstruction at all regions thereof and over which the clothes readily slide during oscillating movement of said agitator.

8. In a washing machine, a receptacle having a substantially flat bottom and an upstanding side wall, an agitator, means for mounting said agitator in said receptacle for oscillating movement about a horizontally extending axis, said agitator including a pair of blades which extend laterally from such axis and project toward said bottom during oscillating movement of said agitator, each of said blades being curved so as to be concave on one side and convex on the other side, and the curvature of one blade with respect to the axis being in a direction opposite to that of the curvature of the other blade with respect to the axis, each of said blades having a lateral extent varying along the axis of the agitator, the maximum lateral extent of one blade being located adjacent to one end of said agitator and the maximum lateral extent of the other blade being located adjacent to the opposite end of the agitator.

9. In a washing machine as set forth in claim 8, in which said receptacle is of cylindrical shape and said agitator is mounted in said receptacle for oscillating movement therein about a horizontally extending axis substantially intersecting the vertical axis of said receptacle.

10. For use in a washing machine, an oscillatable agitator comprising a pair of elongated blades which extend laterally from the axis about which the agitator oscillates, each of said blades having a lateral extent which varies lengthwise of the agitator and being curved so as to define a generally concave-shaped blade surface at one face thereof and a convex-shaped blade surface at the opposite face thereof, and said blades in transverse section being curved in opposite direc-

tions with respect to said axis and having the regions thereof of widest lateral extent offset with respect to one another lengthwise of the agitator.

11. For use in a washing machine, an oscillatable agitator as set forth in claim 10 in which the regions of the blades of widest lateral extent are adjacent to opposite ends of the agitator.

12. For use in a washing machine, an oscillatable agitator as set forth in claim 11 in which the lateral extent of each blade at a centrally disposed region intermediate the ends of the agitator is less than one-half of its widest lateral extent.

13. For use in a washing machine, an oscillatable agitator as set forth in claim 10 in which said agitator is formed of an integral body of material and said convey-shaped blade surfaces are substantially smooth and merge into one another at the region of said axis.

14. For use in a washing machine, as oscillatable agitator as set forth in claim 10 in which the concave-shaped blade surfaces face each other and the remote convex-shaped blade surfaces are at an angle with respect to said axis which is less than 180°, the regions of said blades of widest lateral extent are adjacent to opposite ends of the agitator, and the perpendicular distance from each blade to a plane midway between said blades and intersecting said axis becomes progressively smaller in a direction extending lengthwise of the agitator from the region of each blade of widest lateral extent past a centrally disposed region intermediate the ends of said agitator.

15. For use in a washing machine, an oscillatable agitator as set forth in claim 10 in which the concave-shaped blade surfaces face each other and are of parabolic form and the remote convex-shaped blade surfaces are at an angle with respect to said axis which is less than 180°, the regions of said blades of widest lateral extent are adjacent to opposite ends of the agitator, and the perpendicular distance from each blade to a plane midway between said blades and intersecting said axis is greatest at a region adjacent to and slightly removed from an end of the agitator and is less at the extreme end of the agitator than at a region approximately midway between the ends of the agitator.

16. In a washing machine, the combination of a receptacle for washing fluid and the clothes to be washed, such receptacle having a bottom and an upstanding side wall, an oscillatable agitator comprising a pair of elongated blades which extend laterally from the axis about which said agitator oscillates, each of said blades having a lateral extent which varies lengthwise of said agitator and being curved so as to define a generally concave-shaped blade surface at one face thereof and a convex-shaped blade surface at the opposite face thereof, said blades in transverse section being curved in opposite directions with respect to said axis, mechanism for oscillating said agitator, said agitator being mounted for oscillation in said receptacle so that said blades project toward said bottom during their oscillatory movement and an unobstructed region is provided for a sufficient distance between the outer free edges of said blade and said bottom to furnish adequate space through which clothes can readily pass, and said blades having the regions of widest lateral extent offset with respect to one another lengthwise of said agitator so that one blade promotes circulation of the clothes in one general direction past its outer free edge and the other blade promotes circulation of the clothes in

a generally opposite direction past its outer free edge.

17. In a washing machine as set forth in claim 16 in which said agitator is removably mounted in said receptacle about a horizontally extending axis.

18. In a washing machine, the combination of a receptacle for washing fluid and the clothes to be washed, such receptacle being of cylindrical shape and having a bottom and upstanding side wall, an oscillatable agitator comprising a pair of elongated blades which extend laterally from the axis about which said agitator oscillates, each of said blades having a lateral extent which varies lengthwise of said agitator and being curved so as to define a generally concave-shaped blade surface at one face thereof and a convex-shaped blade surface at the opposite face thereof, said blades in transverse section being curved in opposite directions with respect to said axis, mechanism for oscillating said agitator, said agitator being mounted for oscillation in said receptacle so that said blades project toward said bottom during their oscillatory movement and an unobstructed region is provided for a sufficient distance between the outer free edges of said blades and said bottom to furnish adequate space through which the clothes can readily pass, and said blades having the regions of widest lateral extent offset with respect to one another lengthwise of said agitator so that both blades promote circulation of the clothes in a more or less circular path of movement within said receptacle whereby the clothes are repeatedly brought back again and again to be acted upon by said blades and circulation of the clothes in a path of movement avoiding said blades is minimized.

19. In a washing machine, the combination of a receptacle for washing fluid and the clothes to be washed, such receptacle having a bottom and an upstanding side wall, an oscillatable agitator including two blade-forming portions which extend laterally from the axis about which said agitator oscillates, mechanism for oscillating said agitator, said agitator being mounted for oscillation in said receptacle about a horizontally extending axis so that said blade-forming portions project toward said bottom during their oscillatory movement and an unobstructed region is provided for a sufficient distance between the outer extremities of said blade-forming portions and said bottom to furnish adequate space through which the clothes can readily pass, each of said blade-forming portions having a lateral extent varying along the axis of said agitator, one of said blade-forming portions having an axially extending region of maximum lateral extent disposed between one end of said agitator and a region intermediate the ends thereof and said other blade-forming portion having an axially extending region of maximum lateral extent disposed between the opposite end of said agitator and a region intermediate the ends thereof, and said blade-forming portions being of such shape that one of said blade-forming portions promotes circulation of the clothes in one general direction past its outer extremity and said other blade-forming portion promotes circulation of the clothes in a generally opposite direction past its outer extremity during oscillatory movement of said agitator.

20. In a washing machine, the combination of a receptacle for washing fluid and the clothes to be washed, such receptacle being of cylindrical shape and having a substantially flat bottom

and an upstanding side wall, as oscillatable agitator including two blade-forming portions which extend laterally from the axis about which the agitator oscillates, mechanism for oscillating said agitator, said agitator being mounted for oscillation in said receptacle about a substantially horizontal axis so that said blade-forming portions during their oscillatory movement project toward said bottom and an unobstructed region is provided for a sufficient distance between the outer extremities of said blade-forming portions and said bottom to furnish adequate space through which the clothes can readily pass, each of said blade-forming portions having a lateral extent varying along the axis of said agitator, one of said blade-forming portions having an axially extending region of maximum lateral extent disposed between one end of said agitator and a region intermediate the ends thereof and said other blade-forming portion having an axially extending region of maximum lateral extent disposed between the opposite end of said agitator and a region intermediate the ends thereof, one of said blade-forming portions in transverse section being curved in one direction and said other portion in an opposite direction with respect to said axis so that both portions thereof positively promote circulation of the clothes in a more or less circular path of movement within said receptacle whereby the clothes are repeatedly brought back again and again to be acted upon by said blade-forming portions and circulation of the clothes in a path of movement avoiding said blade-forming portions is minimized.

21. In a washing machine, the combination of a receptacle for washing fluid and the clothes to be washed, said receptacle having a bottom and an upstanding side wall, an oscillatable agitator comprising an integral body of material including a pair of blades which extend laterally from the axis about which said agitator oscillates, each of said blades being curved so as to define a pair of convex-shaped surfaces at one side of said body and a pair of concave-shaped surfaces at the opposite side of said body, said body including an axis-forming region from the immediate vicinity of which said blades project laterally, said body being mounted for oscillation in the receptacle so that said blades project toward said bottom during their oscillatory movement and an unobstructed space is provided for a sufficient distance between the outer extremities of said blades and said bottom to furnish adequate space through which clothes can readily pass, each of said blades having a lateral extent varying along the axis of said agitator, one of said blades having an axially extending portion of maximum lateral extent disposed between one end of said agitator and a region intermediate the ends thereof and said other blade having an axially extending portion of maximum lateral extent disposed between the opposite end of said agitator and a region intermediate the ends thereof, so that one blade promotes circulation of the clothes in one general direction past its outer extremity and the other blade promotes circulation of the clothes in a generally opposite direction past its outer extremity during oscillatory movement of said agitator.

22. In a washing machine, a receptacle, an agitator, means for mounting said agitator in said receptacle for oscillating movement about a horizontally extending axis, said agitator including a pair of blades extending laterally from such axis, each of said blades being curved so as to

be concave on one side and convex on the other side, the concave sides facing a plane which is lengthwise of and between the blades and intersects the axis of oscillation, each of said blades having a lateral extent varying along the axis of said agitator, and one of said blades having an axially extending portion of maximum lateral extent disposed between one end of said agitator and a region intermediate the ends thereof and said other blade having an axially extending portion of maximum lateral extent disposed between the opposite end of said agitator and a region intermediate the ends thereof.

Certificate of Correction

Patent No. 2,491,081

December 13, 1949

CARL OSCAR HALLDIN ET AL.

It is hereby certified that errors appear in the printed specification of the above numbered patent requiring correction as follows:

Column 1, line 24, for the word "cleaning" read *cleansing*; column 7, line 68, for "each" read *such*; column 10, line 16, for "convey-shaped" read *convex-shaped*; line 19, for "machine, as" read *machine, an*; line 53, for "extent" read *extend*; column 12, line 1, for "wall, as" read *wall, an*;

and that the said Letters Patent should be read with these corrections therein that the same may conform to the record of the case in the Patent Office.

Signed and sealed this 28th day of March, A. D. 1950.
